UNITED STATES PATENT OFFICE.

ELWERT COFFMAN, OF LORAIN, OHIO.

MECHANICAL MOVEMENT.

Application filed January 23, 1922, Serial No. 531,124. Renewed June 26, 1925.

To all whom it may concern:

Be it known that I, ELWERT COFFMAN, a citizen of the United States, residing at Lorain, in the county of Lorain and State 5 of Ohio, have invented certain new and useful Improvements in Mechanical Movements, of which the following is a specification.

This invention relates to an improved 10 mechanical movement, and has for its primary object the provision of means for translating oscillatory movement into rotary motion in which the direction of rotation will be uniform and in a single predetermined direction.

With these and other objects in view, as will appear as the description proceeds, the invention consists in the features of construction combinations of elements and arrangements of parts, hereinafter fully described and particularly pointed out in the appended claims.

In the accompanying drawings:

Figure 1 is a side elevation of the device, 25 one set of cover plates being removed.

Figure 2 is a vertical transverse sectional view taken on the line 2—2 of Figure 1.

Figure 3 is a vertical section on the line 30 3—3 of Figure 2.

Figure 4 is a detail view of the operating lever.

Referring more particularly to the details of the invention, the numeral 1 designates a suitable base which includes spaced vertical bearings 2 and 3. Projecting inwardly from the bearing 2 is a stud 8, which is employed to constitute a pivotal mounting or horizontal axis for the reception of an operating lever 10. This lever is adapted to be oscillated about the stud 8 in any suitable manner either by manual or mechanical means. The ends of the bearing 2 are also formed to include studs 11 vertically spaced from the stud 8, and the inner ends of the studs 11 are positioned within arcuate slots 12, formed in the lower part of the lever 10, said slots being on a radius struck from the center of the stud 8 and are situated in relative offset relationship, permitting of the oscillation of the lever within prescribed limits.

The studs 11 project through the slots 12 and comprise axles or gears 13 and 14, the lower gear 14 having the spur teeth thereof arranged for engagement with a cog 15, mounted upon a driven shaft 16, which is

journalized in connection with the bearings 2 and 3, and by the provision of the movement, mechanism is provided for rotating the shaft 16 in a single specified direction, 60 irrespective of the direction of oscillation of the main actuating lever 10. To effect this result, the backs of the gears 13 and 14 include studs or pins 17, which are received within vertically extending slots 18 formed 65 in the lower enlarged part of the lever 10. It will be observed that the pins 17 are eccentrically mounted on the gears 13 and 14 with respect to their true axial centers, and therefore upon the oscillation of the 70 lever 10, rotary movement will be imparted to the gears.

To cause the gears 14 and 15 to rotate in predetermined directions, each of the gears 13 and 14 is formed to include inner and outer 75 sections 19 and 20 respectively. These sections are concentrically situated, the inner section receiving the studs 11, while the outer sections are provided with the gear teeth and will rotate independently of the 80 inner sections. The inner sections are provided contiguous to the peripheries thereof with inclined slots 21, in which are positioned roller elements 22, normally forced toward the reduced ends of said slots by 85 means of springs 23. To retain the inner sections 19 within the sections 20 cover plates 24 are provided, as clearly shown in Figure 2.

By the instrumentality of this construction, it will be seen that in operation when the lever 10 is oscillated, the inner sections of the gear elements will be caused to revolve in unison with the lever by reason of the positive connections existing therebetween provided by the pins 17 and the lever slots 18. However, when the lever is oscillated in the direction indicated by the arrow B, the rollers 22 in the slots 21 provided in the upper of the gear elements will be forced 100 toward the reduced ends of said slots, thereby frictionally uniting the inner and outer sections of the gear element so as to cause said sections to rotate unitarily. This results in imparting power to the lower gear 14, causing its outer section to rotate independently of the inner section, this function being admitted because of the fact that the slots 21 in the lower gear element are 105 reversely disposed with respect to the same slots in the upper gear element. Now, when the lever is oscillated in the opposite direc-

tion the reverse of the above described operation takes place. That is, the roller elements 22 in the lower gear element 14 lock the inner and outer sections of said gear 6 together, thereby causing the latter to continue to rotate in the same direction as the said gear 14 was rotated during the operation of the lever 10 in the direction indicated by the arrow B. This construction 10 provides a simple, powerful and effective means for effecting the rotation of the shaft or other body in a predetermined direction by means of an oscillatory lever.

What is claimed is:

- 15 1. A mechanical movement including a pair of gears, each of said gears including inner and outer sections, axial supports for said inner sections, pins projecting from said inner sections and disposed eccentrically 20 of said supports, an oscillating lever, a pivotal mounting for said lever disposed equidistantly between said supports, said lever having slots therein for the reception of said pins and means situated between the 25 inner and outer sections of said gears for selectively rotating said gears in accordance with the direction of oscillation of said lever.
2. In a mechanical movement, an oscillatory lever, a pivotal mounting for said lever, said lever having slots formed therein on opposite sides of the pivotal mounting therefor, gear elements including independently rotatable inner and outer sections, said 30 outer sections including gear teeth arranged for intermeshing engagement, axial supports for the inner sections of said gears, said supports extending through slots provided in said lever, rigidly mounted pins projecting eccentrically from the inner sections of 35 said gears and arranged to be received within the first named slots provided in said lever, and clutch devices situated between the inner and outer sections of said gears 40 and operative to alternately impart power 45

to said gears upon the oscillation of said lever.

3. In a mechanical movement, a pivotally mounted operating lever, a pair of wheels, each of said wheels including inner and outer independently rotatable sections, the peripheries of said outer sections being disposed in engagement with one another, studs extending axially through said inner sections and arranged to be received within slots formed in said lever, pins eccentrically carried by said inner sections and received within a second pair of slots formed in said lever, and reversely operating clutch devices situated between said inner and outer sections 60 and operating in accordance with the direction of oscillation of said lever to alternately apply power to said wheels.

4. In a mechanical movement, a pair of wheels including inner and outer sections, 65 the outer sections having the peripheries thereof disposed in driving engagement with one another, relatively stantionery supports extending axially through said inner sections and serving to rotatably support the latter, 70 an operating lever pivoted between said supports, pins provided eccentrically upon said inner sections and received within slots formed in said lever, said inner sections having the peripheries thereof formed to include reversely arranged tapering slots, and roller elements positioned within said slots and operating upon the oscillation of said lever to be alternately forced into and out of the restricted ends of said slots, said elements serving when in the restricted ends of said slots to unite the inner and outer sections of the wheel in which they are situated for unitary rotary movement, and when in the enlarged extremities of said slots, to 80 admit of reversely rotative movement of the inner and outer sections of the wheel in which the said elements are situated.

In testimony whereof I affix my signature.

ELWERT COFFMAN
